UNITED STATES PATENT OFFICE.

THOMAS E. DROHAN, OF CHICAGO, ILLINOIS, ASSIGNOR TO THE SIEMENS & HALSKE ELECTRIC COMPANY OF AMERICA, OF SAME PLACE.

ELECTRIC-ARC LAMP.

SPECIFICATION forming part of Letters Patent No. 594,682, dated November 30, 1897.

Application filed July 9, 1897. Serial No. 643,943. (No model.)

To all whom it may concern:

Be it known that I, THOMAS E. DROHAN, a citizen of the United States, residing at Chicago, in the county of Cook and State of Illinois, have invented new and useful Improvements in Electric-Arc Lamps, of which the following is a specification.

My invention relates to an electric-arc lamp; and its object is to provide means for preventing the total release of the carbon when the latter is nearly consumed.

My invention is especially applicable to an arc-lamp wherein one of the carbons loosely fits in a bodily-movable tubular portion, clutch mechanism carried by said tubular portion being adapted to grip said carbon or to release the same to effect regulation of the length of arc. A fault in lamps of this character has been that the clutch mechanism was liable to totally release the carbon, causing it to fall and short-circuit or otherwise damage the lamp. It is to obviate this difficulty without interfering with the sensitiveness of the mechanism which regulates the feeding 25 of the carbon that my invention is designed.

My invention will be readily understood by reference to the accompanying drawing, which is a diagrammatic illustration of an arc-lamp embodying my invention.

In the drawing, *a* represents a solenoid electrically connected in series with the arc, the solenoid having a hollow iron core *b*, provided with a tubular extension *b'*, through which the upper carbon *d* is fed. A slot *b*² is provided near the lower end of the tubular extension *b'*, through which slot the clutch-lever *c* engages with the carbon *d*, being pivoted at *c'* to said tubular extension. The outer end of the lever *c* is enlarged to form 40 a weight *c*². An adjustable stop *e* is provided upon a portion *f* of the frame of the lamp, this stop lying in the path of the enlarged end *c*² of the clutch-lever.

During the burning of the lamp when the 45 ends of the carbons become consumed and the resistance of the arc increased the pull of the solenoid upon its core *b* is lessened, thus allowing the core and the tubular extension thereof to descend by their own weight, 50 whereupon the enlarged end *c*² of the clutch-lever *c* is engaged by the stop *e*, thus releas-

ing the carbon *d* and permitting the latter to fall. Upon the proper length of arc being established the solenoid *a* is actuated to lift its core and the tubular extension thereof, the 55 end *c*² of the clutch-lever *c* being withdrawn from engagement with the stop *e* and the lever caused again to clutch the carbon, checking its further descent.

In order to prevent the carbon when nearly 60 consumed from falling entirely out of the tubular part *b'* and damaging the lamp, I have devised a simple catch mechanism to prevent the release of the carbon after its upper end has passed a given point in its downward path. This consists of a weighted trigger *g*, pivoted at *g'* to a portion of the frame of the machine, the rounded end *g*² of the trigger riding upon the surface of the carbon *d* through a slot *b*³, provided in the tubular part *b'*. This engagement, however, is light and in no way impedes the proper action of the clutching mechanism.

It will be seen upon an inspection of the drawing that when the upper end *d*' of the 75 carbon passes the end *g*² of the trigger the latter will be no longer supported and will fall by its own weight into the slot *b*³, being checked, however, in its further descent by a stop *h*, provided upon the frame of the lamp 80 for this purpose. The tubular extension, being now engaged by the end *g*² of the trigger, is prevented from descending sufficiently to allow the carbon *d* to be released by the engagement of the clutch-lever with the stop *e*. 85 The arc will now simply burn itself out and cause no damage to the lamp.

It will be seen that modifications may be made in my invention over the form shown in the drawing, and I do not, therefore, desire to be limited to this precise construction; but,

Having thus described my invention, what I claim as new, and desire to secure by Letters Patent, is—

1. In an electric-arc lamp, the combination 95 with a longitudinally-movable tubular portion through which the carbon may freely pass, of a clutch-lever pivoted to said tubular portion and normally engaging the carbon, a stop in the path of said clutch-lever adapted to engage therewith and cause the 100

- same to release the carbon, means for preventing the engagement of the clutch-lever with said stop to prevent the total release of said carbon from the tubular portion after it 5 has passed a given point therein, and electromagnetic means for causing the movement of said tubular portion to effect thereby the regulation of the lamp, substantially as described.
- 10 2. In an electric-arc lamp, the combination with a solenoid, of a hollow iron core therefore having a tubular extension through which the carbon may freely pass, a clutch-lever pivoted to said tubular extension and normally 15 engaging the carbon, a stop in the path of said clutch-lever adapted to engage therewith and cause the same to release the carbon, and means for preventing the total release of the carbon after the latter has passed 20 a given point in said tubular portion, substantially as described.
3. In an electric-arc lamp, the combination with a tubular part through which the carbon is adapted to be fed, of a trigger adapted 25 to rest upon the carbon as it is fed through said passage and to engage with said tubular part after the carbon has passed the trigger, substantially as and for the purpose specified.
4. In an electric-arc lamp, the combination 30 with a movable tubular part through which the carbon is adapted to be fed, of clutch mechanism carried by said tubular part, and normally engaging the carbon, a stop in the path of said clutch mechanism adapted to engage therewith to cause the same to release the carbon, means for preventing the release 35

of the carbon after it has passed a given point in said tubular part, and electrically-operated means for causing the movement of said tubular part, to effect thereby the regulation of the lamp, substantially as described. 40

5. In an electric-arc lamp, the combination with a movable tubular portion through which the carbon is adapted to be fed, of clutch mechanism carried upon said tubular portion 45 and normally engaging the carbon, a stop in the path of said clutch mechanism adapted to engage therewith to cause the release of the carbon, a stop adapted to rest upon the carbon as it is fed through said tubular portion and to engage with said tubular portion after the carbon has passed the stop, and electrically-operated means for causing the movement of said tubular portion, substantially as and for the purpose described. 50

6. In an electric-arc lamp, the combination with a solenoid having a hollow iron core, of a clutch-lever carried thereby and normally engaging the carbon, a stop in the path of said clutch-lever adapted to engage therewith and cause the release of the carbon, and a trigger resting upon the carbon as it is fed through said core and to engage with the core after the carbon has passed the trigger, substantially as and for the purpose described. 60

In testimony whereof I affix my signature in the presence of two witnesses.

THOMAS E. DROILAN.
